UNITED STATES PATENT OFFICE.

JAMES CARAFILIDIS, OF SABRATON, WEST VIRGINIA.

TIN-STICKER MACHINE.

1,410,458.

Specification of Letters Patent. Patented Mar. 21, 1922.

Application filed January 25, 1921. Serial No. 439,800.

To all whom it may concern:

Be it known that I, JAMES CARAFILIDIS, a citizen of the United States, residing at Sabraton, in the State of West Virginia, have 5 invented new and useful Improvements in Tin-Sticker Machines, of which the following is a specification.

This invention relates to machines for separating sheets of metal and similar material, 10 and more particularly to what I have termed a "sticking machine".

One of the main objects of the invention is to provide a machine of the character 15 stated of simple construction and operation which may be readily worked by a single operator. A further object is to provide a machine having means for gripping sheets of metal and for tearing the same apart. Further objects will appear from the detailed 20 description.

In the drawings:

Figure 1 is a front view of a machine constructed in accordance with my invention.

Figure 2 is a section taken substantially 25 on line 2—2 of Figure 1.

Figure 3 is a detail of the grippers.

Figure 4 is a central vertical section 30 through the machine taken from front to back.

Figure 5 is an end view of the machine.

Figure 6 is a fragmentary detail showing the latch for holding the lever depressed.

It is the present practice in rolling mills to 35 roll iron and similar metals in sheets which come from between the rolls in stacks or masses, these sheets after they leave the rolls being torn apart or separated by hand, this operation being termed "sticking". The primary object of this invention is to provide a 40 machine of simple construction by means of which this sticking operation may be performed more quickly and easily than by hand. With this object in view I provide a

boxlike casing 1 which is supported by a 45 suitable frame 2 mounted on casters 3 so as to be readily moved toward or away from the mass or stack of sheets. Two gripping members 4 of plierlike construction are slidably mounted in casing 1, the heads 5 of 50 these members projecting through a slot 6 extending longitudinally of the back wall 7 of the casing. Each arm of pliers 4 is provided with a supporting caster 8 to facilitate

movement of the gripping members toward and away from each other. The forward 55 end portions of the arms of the gripping members slide on a guide strip 9 secured in the front of casing 1, and outward movement of these members is prevented by a stop strip 10 which projects above strip 9. The members 4 are normally held in open position by expansion springs 11. Each arm of member 4 is provided at its forward end with an upwardly projecting peg or pin 12, these pins being positioned directly below a bell-shaped 60 member 13 slidably mounted on a bar 14 extending longitudinally of casing 1 at the front thereof. This bar is connected at one end by a link 15 to a bracket 16 secured to the end of the casing. An expansion spring 70 17 confined between link 15 and the adjacent end of casing 1 co-operates with an expansion spring 18 mounted in a slot in the other end of the casing and confined between the same and bar 14 to hold the bar raised. A 75 lever 19 is pivoted at 20 in a bracket 21 secured to end 1^a of casing 1, and extends across bar 14 which projects through the end wall of the casing. This lever extends through a slot 21 in a bracket 22 secured 80 to end 1^a of the casing at the back thereof, this slot being inclined downwardly and inwardly toward the casing. Lever 19 fits into a notch 23 in bar 14 so that when the lever is depressed it causes downward and inward 85 movement of bar 14 due to the inclination of slot 21. This serves to force the members 13 over pins 12 forcing the pins toward one another and thus closing the heads 5 of members 4 so as to cause them to grip a sheet inserted between the jaws 5^a. A gravity latch 19^a (Fig. 6), or any other suitable means 90 may be provided for holding lever 19 depressed.

Each of the members 4 is connected by a 95 tension spring 24, and links 25 and 26 to one end of casing 1 in such manner that the springs 24 act to normally hold members 4 in position centrally of the casing as illustrated, these members being open and the 100 inner jaws 5^a of the heads 5 fitting closely together so as to provide in effect an inner or central wedge shaped member and two outer wedge members which are well adapted to be forced between sheets of a stack 105 which is stood on edge. After this has been

done, the gripping members are closed in the manner described so as to grip the sheets between jaws 5^a, after which the members 4 are forced away from each other toward the ends of the casing thus tearing the sheets apart.

For the purpose of forcing members 4 away from each other I provide a toggle structure 27 consisting of pairs of links 28 and 29 which are pivotally connected at their outer ends at 30. The lower end portions of links 29 intersect and are pivoted at 31 to studs 32 secured to the inner arms 4^a of members 4. The lower ends of links 28 project beyond links 29 and are shaped to provide forks 33 which carry rollers 34 which travel between guide strips 35 secured to the inner faces of the end walls of casing 1. The links 28 are pivoted at their upper ends, at 36 to the lower end of a plunger 37 slidable through top 1^b of casing 1. This plunger is provided at its upper end with fork 38 between which and the top of the casing is confined an expansion spring 39 mounted about 40 the plunger. A lever 40 is pivoted at its inner end to a standard 41 secured to the top wall of the casing, and is connected by pin and slot connections 42 to fork 38. At its outer end lever 40 is pivoted, at 43, to a fork 44 carried by a pull rod 45 to the lower end of which is loosely connected a treadle 46.

In using the machine, the stack of sheets is placed on edge after which the machine is moved into position adjacent to the front 35 of the stack and is then forced toward the stack so as to force the jaws 5^a of the gripping members between the sheets. The gripping members are then closed so as to tightly grip the sheets between the jaws, after which 40 plunger 37 is depressed by pressing on treadle 46 thus forcing the gripping members 4 away from each other and tearing the sheets apart. During this operation, the members 13 travel freely on bar 14 to a 45 greater or less extent. The jaws 5^a of the gripping members 4 may be closed or opened to the desired extent for gripping the desired number of sheets. After the sheets have been separated, by releasing treadle 46 50 from pressure and releasing lever 19, the gripping members and associated parts and the members 13, are permitted to return to normal position, this being effected by the springs 24 and 17 and 18 and spring 39.

55 The jaws 5^a of the gripping members are preferably, though not necessarily, provided with face plates 47 of hard steel which are removably secured by screws 48, or in any other suitable manner thus permitting renewal of these jaws when desired. This is a desirable feature of the invention since the gripping faces and points of the jaws are subjected to great wear and strain in use.

As will be understood, slight changes in 65 construction and arrangement of parts of

the invention may be resorted to without departing from the field and scope of the same, and I intend to include all such variations, as fall within the scope of the appended claims, in this application in which 70 a preferred form only of my invention is disclosed.

What I claim is:

1. In a machine of the character stated, a casing, gripping members slidably longitudinally of the casing, means for normally holding said members adjacent to each other, means for normally holding the gripping members open, means for closing the gripping members and permitting movement of 80 the same longitudinally of the casing, and means for moving the gripping members in opposite directions. 75

2. In a machine of the character described, a casing, gripping members slidably mounted in the casing for movement toward and away from each other, the casing being provided through its back wall with an elongated slot and the heads of said members projecting through said slot, means for preventing movement of the gripping members toward the front of the casing, means for normally holding the gripping members adjacent to each other, means for normally holding the gripping members open, means for closing the gripping members and permitting movement of the same away from each other, and means for forcing said gripping members in opposite directions. 85 90 95

3. In a machine of the character described, a casing provided through its back wall with an elongated slot, gripping members of plierlike construction slidable in the casing for movement toward and away from each other and having their heads projecting through said slot, means for normally holding said members open, means for holding the gripping members in positions adjacent to each other, means for closing the gripping members while permitting movement 100 of the same away from each other, and means for forcing the gripping members away from each other. 105 110

4. In a machine of the character described, a casing provided through its back wall with a longitudinally extending slot, gripping members of plierlike construction slidable longitudinally of the casing and having their heads projecting through said slot, means for normally holding the arms of the gripping members apart, pins projecting upwardly from the arms of the gripping members, upwardly tapering members adapted to fit over the pins when depressed and to force said pins toward each other, means for supporting said upwardly tapering members for independent movement longitudinally of the casing and for depressing and raising the same, means for normally holding the gripping members in positions 115 120 125 130

adjacent to each other, and means for forcing the gripping members away from each other.

5. In a machine of the character described, a casing provided through its back wall with a longitudinally extending slot, gripping members of plierlike construction movable longitudinally of the casing and projecting through said slot, means for normally holding the arms of the gripping members apart, said arms being provided with upwardly projecting pins, a bar extending longitudinally of the casing and supported above the pins, said bar being vertically movable, upwardly tapering members supported on the bar and freely movable longitudinally thereof, said members being adapted when the bar is depressed to engage over said pins so as to force the same toward each other, means for depressing said bar, means for normally holding the gripping members in

positions closely adjacent to each other, and means for forcing the gripping members apart.

6. In a machine of the character described, a casing, gripping members slidably mounted in the casing, said members being of plierlike construction and having the jaws of their heads of wedge shape, means for normally holding the gripping members open, means for normally holding the gripping members in positions closely adjacent to each other with the inner jaws of said members in contact so as to form a central wedge positioned between the outer jaws of the gripping members, means for closing the gripping members and for permitting movement of the same in opposite directions, and means for moving the gripping members away from each other.

In testimony whereof I affix my signature.
JAMES CARAFILIDIS.
